DESIGN FOR A LAWN MOWER

Paul C. Young and Marion F. Crawford,
Kansas City, Mo.

Application March 23, 1936, Serial No. 61,745

Term of patent 7 years

To all whom it may concern:

Be it known that we, Paul C. Young and Marion F. Crawford, citizens of the United States, residing at Kansas City, in the county of Jackson and State of Missouri, have invented a new, original, and ornamental Design for Lawn Mowers, of which the following is a specification, reference being had to the accompanying drawings forming part thereof, in which:

Fig. 1 is a perspective view of a lawn mower showing our new design.

Fig. 2 is a side elevation thereof.

We claim:

The ornamental design for a lawn mower, as shown.

PAUL C. YOUNG.

MARION F. CRAWFORD.
